UNITED STATES PATENT OFFICE

WALTER M. CROSS, OF KANSAS CITY, MISSOURI, ASSIGNOR TO GASOLINE PRODUCTS COMPANY, INC., OF JERSEY CITY, NEW JERSEY, A CORPORATION OF DELAWARE

CLEANING PLUG

Application filed May 10, 1926. Serial No. 107,914.

This invention relates to improvements in cleaning plugs, and refers more particularly to plugs adapted to be placed in the casing or assembly at the ends of tubes through which 5 is passed liquid or fluid medium to be heated.

Among the salient objects of the invention are, to provide an assembly in which are cleaning plugs which are readily removable and plugs which prevent contacting of medium with the screw or threaded joints which 10 serves to hold the plugs rigidly in place; to provide a double plug arrangement comprising a stationary inner plug seated upon a tapered ground joint, the angle of the joint 15 being such as to assure pressure-tight fit and at the same time facilitate removal of the plug and a movable outer holding plug screwed in the casing into which the tubes are expanded having a convex central portion 20 adapted to contact with a concave portion of the inner stationary plug.

Referring to the drawings:

Fig. 1 is a sectional side view of the tube end assembly.

25 Fig. 2 is an end view of the assembly shown in Fig. 1.

Fig. 3 is an outer end view of the inner stationary plug.

Fig. 4 is an inner end view of the movable holding plug.

Referring to the drawings, the tubes 1 are expanded into a casing or fitting 2. Opposite the ends of the tubes are apertures having substantially the same inner diameter as 35 the tubes. These apertures or holes opposite the ends of the tubes have tapered ground joints 3. Into these holes are fitted stationary plugs 4 which are tapered at 4^a to fit the tapered ground joints 3. The outer 40 face of the stationary or inner plug has a concave surface 5 which is contacted by the convex surface 6 of the outer movable holding plug 7. This outer plug is threaded with square threads adapted to engage the threads 45 cut in the fitting tube. The outer faces of the holding plugs have hexagonal sockets for tightening or loosening the holding plugs 50 by means of a socket wrench not shown. A central threaded hole 8 drilled in the inner plug furnishes a means for removing the

inner plug by means of a I bolt which is screwed into the inner stationary plug after the removal of the outer holding plug. The holes 9 in the outer face of the stationary or inner plug may be fitted by a spanner wrench for grinding in the surfaces of the ground seat on the fitting and plugs. The plugs used opposite the tubes are identical in construction and therefore a description of a single plug will suffice for all.

The use of a double plug arrangement of this character prevents the leaking of any of the medium by the inner plug to contact and corrode or clog the screw or threaded joint between the outer holding plug and the fitting; therefore, the outer plugs may be easily unscrewed or tightened without tendency to freeze or become corroded in place due to the action of chemical contained in the medium which is being treated upon the 70 steel.

Furthermore, by the use of two plug sections,—one ground to a pressure-tight fit with the fitting, while the other functions as a holding member primarily and the threaded section is not depended upon to assure the pressure-tight closure. The wearing of threads due to a continual removal and replacement of the plugs produces a construction unsafe under high pressures.

As suggested, the angle of the tapered ground joint is such as to assure a pressure tight fit and permit the easy removal of the inner plugs. An angle adapted to produce this effect is substantially 30° from the 85 horizontal.

Particularly with reference to pipe stills in connection with treatment of hydrocarbon oils, the threaded connection between plugs and tube end fittings become coked up and 90 rigidly lodged in place so that it is necessary oftentimes to drill out the plug from the fitting. Plugs of this character are adaptable to any type of heating system in which a fluid medium is being treated for use in tube end 95 fittings.

I claim as my invention:

A tube header assembly comprising a header having opposite walls, one of said walls having tube receiving openings there-

in, the other wall having cleanout openings directly opposite the tube receiving openings, a peripheral edge of said cleanout openings being tapered to form a plug receiving seat, 5 a disc-like plug having a reduced portion adapted to enter the cleanout openings, and an enlarged portion ground to fit the receiving seat, said plugs having a shallow concave recess formed in the outer surface there-
10 of, tubular internally threaded protuberances surrounding the cleanout openings, one-piece imperforate followers threaded into the protuberances, tool receiving means formed on one side of the followers, and con-
15 vex projections centrally formed on the inner side thereof adapted to engage the recesses in the plugs to position and secure the plugs in the cleanout openings.
